UNITED STATES PATENT OFFICE

2,475,400

HOOD FOR SUCTION CLEANERS AND
THE LIKERalph C. Osborn, Bloomington, Ill., assignor to
Eureka Williams Corporation, Bloomington,
Ill., a corporation of Michigan

Application April 23, 1947, Serial No. 743,478

8 Claims. (Cl. 40—130)

1

This invention relates to vacuum cleaners and has particular reference to a new and improved construction for the hood thereof.

In suction cleaners as now commonly built a hood is employed to cover the motor of the cleaner and the light thereof, and of necessity must be provided with a suitable window through which light rays are directed forwardly of the cleaner for illuminating the surface in front of the cleaner and on which it is operating.

This invention contemplates a new and simplified construction for the hood in which the light transmitting window is formed integrally with the hood. This arrangement reduces the cost of manufacture and makes it possible to achieve certain design effects which it is now impractical to attain.

The invention further contemplates the feature of making a name or design plate for the cleaner integral with the hood so as to reduce the cost thereof and also for the purpose of making it possible to achieve certain design effects it is now impractical to attain.

Principal objects of the invention, therefore, are to provide:

A new and improved hood for a suction cleaner;

A new and improved hood for a suction cleaner in which a light transmitting lens and a name or design plate are made integrally with the hood.

Other objects and advantages of the invention will be apparent from a consideration of the following specification taken in conjunction with the accompanying drawing, of which there is one sheet and wherein:

Fig. 1 is a side elevational view of a cleaner embodying the invention with the hood thereof shown in section;

Fig. 2 is a fragmentary plan view of the hood;

Fig. 3 is a fragmentary bottom plan view of the hood; and

Fig. 4 is an enlarged fragmentary sectional view through the name plate.

As shown in Fig. 1, a vacuum cleaner embodying the invention comprises a body 10 having front and rear supporting wheels 12 and 14 and a propelling handle 16 pivoted to the cleaner. The cleaner further includes a motor 18, a light 20, and a motor hood 22. The hood 22 is seated upon the body 10 and is arranged to cover the motor 18 and light 20 and to complete the appearance of the cleaner. It is provided with a slot 24 for the handle socket, a lens or light transmitting window 26, and a name plate indicated generally at 28.

The hood, lens and name plate according to

2

the invention are molded in one piece from a transparent material, such as a thermoplastic material and preferably one which has the property of "piping" light. Methylmethacrylate is an example of a suitable transparent material which has the property of "piping" or transmitting light through and around curved surfaces.

The hood 22 is formed in a suitable mold so as to define the portion 26 which forms the lens and 10 also to define the name or design plate portion 28 which has hollow letters or other suitable indicia molded into the material of the hood on the underside, as shown in Figs. 1, 2 and 4. The indicia may however be formed after the hood is formed, 15 if desired, by any suitable process.

Preferably a boss 29 is formed on the inside of the lens 26 and has a surface facing the light 20 so that light will be more readily piped down the front of the hood to the indicia of the name 20 or design plate portion 28.

After the hood 22 is removed from the mold the lens area on the underside of the hood is masked. The surfaces 31 and 33 defining the hollow embossed indicia or letters also are masked, 25 such as by filling with a low melting point wax. Thereafter the underside of the hood is given a coat of paint of the desired color, as indicated by the heavy line 36, such as by spraying, and which paint because of the transparency of the 30 hood material will be visible from the outer or top side of the hood and give the hood its color. The wax is then melted out of the hollow embossed indicia and the lens mask removed. Thereafter a strip of material 30 of a contrasting color 35 to the finished hood is placed in the recess formed by the molded boss 32. The plate 30 may be held in position by melting the thermoplastic of the boss 32 so as to form stakes 34 for holding the plate 30 in position.

When the hood is assembled to the cleaner with the light 20 illuminated, the hood will only 40 transmit light through the lens portion 26. This portion may comprise the embossed area lying between the spaced dotted lines shown in Fig. 1.

The lens area preferably is located centrally of 45 the front of the hood and extends throughout a substantial range on both sides of the center, as indicated in Figs. 2 and 3. The paint 36 on all the remaining undersurface of the hood prevents light from showing through the hood except through the lens 26 and on the letters or figures of the name or design plate.

Since the methacrylate plastics have light 50 piping properties, the edge surfaces 31 of the hollow embossed indicia arranged transversely

of the plane of the hood material will be lighted by the rays of light transmitted or piped through the material of the hood to provide a vertical edge-lighting effect on the letters or figures of the name or design plate. The color of the plate 30 will be visible from the top side of the hood so that when the light 20 is off, the name or design plate will be formed by the color of the plate 30 showing through the surfaces 33 of the hollow embossed indicia in the hood. The contrasting color of the plate 30 relative to the paint 36 will thus provide a color backing for the letters forming the name plate.

Instead of using a separate color backing plate 30, a name or design plate may be formed on the hood by painting the surfaces 31 and 33 a color which contrasts with the color of the paint coat 36. However, if the edge surfaces 31 are left unpainted and the horizontal surfaces 33 painted a color contrasting with that of the paint coat 36, a vertical edge lighting effect for the figures or letters of the name or design plate like that previously described may be obtained. As the paint 36 is on the underside of the hood, it will not be subject to scratching and abrasion during shipment and use.

While I have illustrated and described a preferred embodiment of my invention, it is understood that this is capable of modification, and I therefore do not wish to be limited to the precise details set forth, but desire to avail myself of such changes and alternations as fall within the purview of the following claims.

I claim:

1. A vacuum cleaner having a motor and a light, a hood comprising an integral molded dome-shaped piece of plastic material arranged to cover said motor and light, said material being transparent and having the property of piping light, said hood having an integral portion at the front thereof defining a light transmitting lens for the light so as to direct light rays forwardly of the cleaner, said hood having indicia formed into the material of the hood on the under side thereof and spaced from said lens, a coat of coloring on said hood except for the lens portion, said indicia being formed and arranged so that edge surfaces thereof extending in a plane transversely of the surface of the hood are uncolored and will be lighted by the rays of the light transmitted through the material of the hood due to the light piping characteristic thereof to provide an edge lighting effect on said indicia.

2. A vacuum cleaner according to claim 1 wherein a color backing is arranged on the underside of surfaces of said indicia extending generally parallel to the plane of the portion of the hood in which said indicia is formed.

3. In a vacuum cleaner having a motor and a light, a motor hood comprising an integral molded piece of transparent plastic material having a coat of coloring on its under surface and having a light transmitting window for the light so as to direct light rays forwardly of the cleaner, said hood having indicia molded into the material of the hood on the under side thereof and spaced from said window, said material having the property of piping light, said indicia being arranged so that the edge surfaces thereof extending in a plane transversely of the surface of said hood are

uncolored and will be lighted by the rays of light transmitted through the material of the hood to provide an edge lighting effect for said indicia.

4. A vacuum cleaner according to claim 3 wherein a color backing is arranged on the underside of the surfaces of said indicia extending generally parallel to the plane of the portion of the hood in which said indicia are formed.

5. In a vacuum cleaner having a motor and a light, a motor hood comprising an integral molded dome-shaped piece of transparent plastic material having its under surface painted except for a limited area at the front of the hood, said area defining a light transmitting lens for the light so as to direct light rays forwardly of the cleaner, said hood having indicia molded into the material of the hood on the under side thereof and spaced from the said lens, the surfaces defining said indicia being uncolored, said material having the property of piping light, said indicia being arranged so that edge surfaces thereof extending in a plane transversely of the surface of said hood will be lighted by the rays of light transmitted through the material of the hood to provide an edge lighting effect on said indicia.

6. In a vacuum cleaner having a motor and a light, a motor hood comprising a molded dome-shaped piece of transparent plastic material having its inner surface painted and an area at the front of the hood defining a light transmitting window for said light source, said hood being formed of material having the property of piping light and having indicia molded therein lighted by the rays of light transmitted through the material of said hood.

7. A vacuum cleaner according to claim 1 wherein said hood is provided with a boss having a surface facing said light so as to facilitate the passage of light rays into the material of said hood.

8. A vacuum cleaner having a motor and a light, a hood comprising an integral molded dome-shaped piece of plastic material arranged to cover said motor and light, said material being transparent and having the property of piping light, said hood having an integral portion at the front thereof defining a light transmitting lens for the light so as to direct light rays forwardly of the cleaner, the under surface of said hood except for said lens being painted, said hood having indicia molded into the material of the hood on the under side thereof and spaced from said lens, said indicia having a color backing of a contrasting color relative to the color which the under surface of the hood is painted.
